UNITED STATES PATENT OFFICE.

MAURICE S. SULLIVAN, OF MERIDEN, CONNECTICUT.

NURSING-BOTTLE HOLDER.

Application filed August 4, 1926. Serial No. 127,054.

This invention relates to new and useful improvements in holders or supports for nursing bottles when in use and has for its primary object to provide a holder whereby 5 the bottle is supported in a properly tilted position when the baby is within a carriage or crib so that the contents thereof may be readily taken by the child without requiring the holding of the bottle by the mother, 10 nursemaid, or other attendant.

A further object of the invention resides in the provision of a holder of this character that is constructed for ready association with the conventional designs of nursing 15 bottles and one that may as readily be removed therefrom.

A further and important object is to provide a holder consisting of means for disposition upon the bottle as well as means 20 whereby the bottle may be suspended from the crib or carriage, said means being co-operatively constructed so that the bottle will not become disengaged from the holder when the same is in use.

25 Other objects will become apparent as the nature of the invention is better understood, the same comprising the novel form, combination, and arrangement of parts hereinafter more fully described, shown in the 30 accompanying drawing and claimed.

In the drawings herein like numerals indicate like parts.

35 Figure 1 is a side elevation of a nursing bottle holder constructed in accordance with the present invention, the same being disclosed as actually in use.

40 Figure 2 is a longitudinal section taken substantially upon the line 2-2 of Figure 1 for disclosing in top plan the means with 45 which the bottle is directly associated.

Figure 3 is a view in side elevation disclosing the elements that are directly attached to the bottle in the act of being applied to or removed therefrom, and

45 Figures 4 and 5 are perspective views of the members constructed for disposition upon the bottle.

50 Now having particular reference to the drawing, my novel nursing bottle holder constitutes the provision of a pair of wire frame members designated generally by the numerals 5 and 6 respectively, said frame members being constructed for disposition upon the bottle A at the opposite ends 55 thereof.

The frame member 5 is formed from a

single length of steel wire so bent as to provide a relatively oval shaped loop 7 at one end of the frame for engagement over the neck of the bottle A and a large oval 60 shaped loop 8 at the opposite end of the frame for engagement around the body of the bottle A, the wire forming the frame member 5 is coiled as at 9 and 10 so as to provide a spacing means between the loops 65 7 and 8 at opposite sides thereof.

The wire forming the frame member is so bent at one side of the loop 8 as to provide a pair of lateral eyes 11-11 within which the ends of the strand of wire that 70 extend from the adjacent ends of the coil 9 are arranged as clearly disclosed in Figure 4. Intermediate these eyes 11-11 is a vertically extending eye 12 for a purpose hereinafter more fully described.

75 As more clearly disclosed in Figures 1 and 3, the lower connecting coil 10 between the loops 7 and 9 is slightly shorter than the length of the upper connecting coil 9, so that the body loop 8 will extend diagonally with respect to the transverse axis of the bottle when this frame member 5 is disposed thereon. The length of the frame member 5 is such that the loop 8 will be positioned upon the body of the bottle rearwardly of the center thereof so that the 80 bottle will be supported in an inclined manner as disclosed in Figure 1 as hereinafter more fully described.

85 The frame member 6 is also constructed from a single length of steel wire so bent as to provide an oval shaped loop 13 for engagement over the body of the bottle A rearwardly of the frame member 5. The wire extending from the bottom side of this loop 90 is coiled as at 14, the same being directed rearwardly as at 15, upwardly as at 16 and thence forwardly as at 17 for engaging beneath the bottom side, upwardly along the rear end and thence forwardly over the top 95 side of the bottle as clearly indicated in Figure 1. The ends of the wire are then disposed diagonally outwardly as at 18-18 and are secured within spaced rearwardly extending eyes 19-19 formed in the top 100 side of the loop 13. In this instance also the coil portion of the wire at the bottom side of the frame is shorter than the entire area of the wire at the top side of the frame so that the loop 13 will be positioned diagonally with respect to the transverse axis of 105 the bottle A, as shown in Figures 1, 3 and

110

5. Intermediate the eyes 19—19 of the loop 13, the wire forming the same is so bent as to provide a vertically extending eye 20.

Arranged through the eyes 12 and 20 of 5 the frame members 5 and 6 respectively is an elongated wire link 22, one end of which is formed with an eye 23 to which is secured one end of a coil spring 24. To the opposite end of this coil spring is attached a chain 10 length 25 to which is slidably secured a hook 26 that is preferably constructed for engagement within the wicker material of carriage tops or upon a cross wire stretched between the upper side rails of a crib as suggested in 15 Figure 1.

In order to position the frame members 5 and 6 upon the bottle A it is necessary that the link 22 be moved to the horizontal position as disclosed in Figure 3, after which the 20 frame members may be separated. The frame member 5 is then arranged upon the forward portion of the bottle after which the frame member 6 is disposed over the rear end of the bottle. The link 22 is now swung upwardly and due to its shape will cause the frame members to be drawn toward each other and when the hook 26 is disposed upon the crib rails or carriage structural bar, the 25 weight of the bottle as well as the frame members will prevent the link from turning and consequently the frame members will not separate to permit the bottle to disengage therefrom.

I have previously stated that the hook 26 30 is slidably attached to the chain length 25. This is for the purpose of permitting the length of the hanger unit to be adjusted at will. After the proper adjustment of the hook with respect to the chain length a hook 40 27 upon the end of the chain length is engaged within one of the lengths of the chain so as to prevent the sliding of the hanger hook 26 with respect thereto when the bottle is supported in hanging relation with the 45 crib or carriage.

By closely inspecting Figure 1 of the drawings it will be readily appreciated that the length of the frame members 5 and 6 is such that when the bottle is supported in 50 hanging relation, the same will be maintained in the properly tilted position for use

so that the contents thereof may be readily taken by the child without requiring the holding of the same as stated in the objects of the invention.

55

Even though I have herein shown and described the invention as consisting of certain structural elements, and of a preferable formation, it is nevertheless to be understood that said structural elements as well as the 60 formation thereof may be changed to some extent without affecting the spirit and scope of the appended claims.

Having thus described the invention, what I claim as new and desire to secure by Letters 65 Patent is:

1. In a holder for nursing bottles, a pair of separate frame members constructed for disposition upon the bottle at opposite ends thereof, eye members at the inner ends of 70 said independent frame members, an elongated link independent of the frame members, and slidable through the aforementioned eyes for drawing the frame members together toward each other upon the bottle when the link is swung to a position at right angles with respect to its initial position, and means associated with one end of the link for facilitating the suspension of the bottle 75 from a support.

2. In a holder for nursing bottles, a pair of separate frame members constructed for disposition upon the bottle at the opposite ends thereof, each of said frame members being composed of a single strand of wire 80 so bent as to provide a loop at the inner end of each frame, the outer end of each frame being so constructed as to fit over the neck and rear end of the bottle respectively, the looped inner opposed ends of the frame being disposed around the intermediate portion 90 of the bottle, an eye member formed on the top of the inner end of each frame, a link slidable through the inner opposed eye members and adapted to move the frames toward 95 each other on the bottle when swung in a position at right angles to its initial position, and means connected to the link for suspending the bottle and the holder therefor from a support.

In testimony whereof I affix my signature.

MAURICE S. SULLIVAN.
